FILM REEL HUB INSERT BUSHING

Norman P. Goldberg, Charles H. Cohen, Eugene D. Goalstone, and Seymour Goldberg, Denver, Colo., assignors to Goldberg Brothers, Inc., Denver, Colo., a corporation of Colorado

Filed Apr. 11, 1969, Ser. No. 16,689

Term of patent 14 years

Int. Cl. D16—99

U.S. Cl. D61—1

FIG. 1.

FIG. 3.

FIG. 2.

FIG. 1 is a front view of the film reel hub insert bushing showing our new design;

FIG. 2 is a back view thereof;

FIG. 3 is a side view thereof, the other side, top, and bottom views being mirror images.

We claim:

The ornamental design for a film reel hub insert bushing, as shown and described.
